(57) CLAIM

The ornamental design for a sign holder with a multiple use adhesive surface, as shown and described.

DESCRIPTION

FIG. 1 is an upper perspective view of the sign holder with a multiple use adhesive surface showing my design.

FIG. 2 is a front elevation view thereof;

FIG. 3 is a back elevation view thereof;

FIG. 4 is a side elevation view thereof;

FIG. 5 is an opposite side view thereof;

FIG. 6 is a top plan view thereof;

FIG. 7 is a bottom plan view thereof;

FIG. 8 is still another upper perspective view thereof, showing an opened position of an end thereof;

FIG. 9 is a second embodiment of FIG. 1, the only difference being the dimensions of width and length, it being understood that all other views of surfaces are the same as those of the first embodiment with corresponding dimensions;

FIG. 10 is a third embodiment of FIG. 1, the only difference being the dimensions of width and length, it being understood that all other views of surfaces are the same as those of the first embodiment with corresponding dimensions; and,

FIG. 11 is a fourth embodiment of FIG. 1, the only difference being the dimensions of width and length, it being understood that all other views of surfaces are the same as those of the first embodiment with corresponding dimensions.

The pattern on the back surface in FIG. 3 represents a tacky surface.
